CLOSURE OPERATOR

Filed July 14, 1947

UNITED STATES PATENT OFFICE

2,534,525

CLOSURE OPERATOR

James F. Molloy, Oakland, Calif.

Application July 14, 1947, Serial No. 760,755

5 Claims. (Cl. 121—41)

1

This invention relates to closure operators and more particularly to garage door openers.

Among the objects of the invention is the provision of means for opening garage doors by remote control.

Another object is to delay the closing of garage doors by a selective time interval under positive control.

Another object is the provision of a door opening mechanical unit mounted upon a base board and adapted to be connected and adjusted to various sizes and types of garage doors.

Another object is the utilization of domestic water service for fluid pressure and electric service for remote control power for opening the door.

A further object is to enable the manual operation of the door without interfering with the automatic opening means.

Further objects and advantages will appear as the description proceeds. In the specification and the accompanying drawings the invention is disclosed in its preferred form. But it is to be understood that it is not limited to this form; because it may be embodied in modifications within the spirit of the invention as defined in the claims following the description.

In the one sheet of drawings:

Fig. 1 is a front elevation of a garage door opener constructed in accordance with this invention and applied to a horizontally pivoted door.

Fig. 2 is an enlarged detail in side elevation, partially in vertical section of the hydraulic cylinder unit, and remote electrical control.

In detail the structure shown in Fig. 1, comprises the conventional garage door 1, having the inner side brackets, such as 2, swinging on horizontal pivots such as 3, projecting from the side walls such as 4. The weight of the door is counterbalanced by side springs such as 5, anchored to the adjacent walls 4 and the brackets 2.

Normally the closed door rests upon the garage floor and the upper and side margins of the door are vertically aligned with the inner face of the door frame. The outer face of the lower portion of the door is provided with a handle by which the counterbalanced weight of the door may be manually swung on the pivots 3, until the door is in the substantially horizontal position, as in Fig. 1.

The door opening mechanism comprises the base board 6 fixed to the studding of the wall 4 and has the larger sheave 7 fixed on the stud shaft 8 which has its inner end stepped in a bearing on the base board, with the periphery of the sheave substantially in alignment with the inner plane of

2

the door 1, at any suitable distance behind its top edge 9. The stud 8 extends through the bracket 10, bolted to the base board 6, at 11, 12, to give stability to the stud and the sheave 7. The sheave type pulley guide 13 is mounted on the inner top edge of the door as at 9.

The flexible steel cable such as "tiller rope" 14 has its inner end anchored to the sheave at 15 and its outer end passed through the pulley case guide and, fixed in the coupling 16, the end of which abuts the pulley case at 13. For a door of conventional height, about seven feet, the cable makes two or more turns around the sheave 7.

The take up spring 17 has its rear end fixed to the coupling 16 and its front end anchored to the door at 18. Should the door be manually opened without the hydraulic lift, it is the function of this spring to take up the slack, by pulling the cable end through the pulley casing 13 and prevent the cable slack from dislodging from the sheave 7.

The smaller driven sheave 19 has its hub fixed to the stud shaft 8 and revolves in unison with the larger sheave 7. It is driven by the steel cable 14 having its inner end anchored to the sheave 19 and its outer end fixed in the coupling 21 threaded on the end of the piston rod 22. This rod passes through the stuffing box 23 in the head 24 on the end of the cylinder 25 having the head 26 on its rear end. These heads function as brackets for attaching the cylinder assembly to the base board 6.

The piston 27 is threaded on the inner end of the piston rod and has the cup leather packing 28 held in position against the piston head by a washer and the lock nut 29. The end of the piston rod has the axial bore with the side inlet 30, and outlet 31 with its capacity adjustably controlled by the needle valve 32, threaded into the axial bore. This controlled bypass through the piston drains into the head 26 from which the liquid is carried away through the drain pipe 33.

Water or fluid pressure from the city service or other source is introduced into the cylinder 25, through the inlet 34, the magnetic valve 35, the intermediate sleeve valve 36 and the tube 37, discharging through the head 24, into the cylinder ahead of the piston 27. The stop valve 35 has the magnetic control 38, in the form of a solenoid which lifts the valve stem and opens the valve 35, when the remote control switch 39 closes the electric circuit having the inlet and outlet wires 40, 41 wound around the magnetic control 38. The remote control switch 39, may be mounted upon a post 42 at the side of the drive-

way, on an adjacent building or any location convenient to the driver of an automobile approaching the door 1.

The sleeve valve 36 has the open ended sleeve 43 driven forward by the incoming water pressure against the tension of the soft spring 44, which closes the outlet 45 leading into the cylinder 25 ahead of the piston 27. This outlet 45 has the adjustable needle valve control 46.

The starting spring 47 encircles the piston rod between the stuffing box 23 and the adjustable collar 48 fixed on the piston rod by the setscrew 49. It functions to overcome the inertia of the piston 27, before the door begins its descent.

This invention operates substantially as follows: When the door 1 is in the vertical closed position, the cable 14 is in the extended condition and the piston nut 29 advanced to abutment with the end of the stuffing box 23 projecting into the cylinder 25, permitting an unobstructed inflow of water from the tube 37 ahead of the piston.

Closing the switch 39, opens the valve 35 admitting water pressure through the valve 36, which causes the sleeve 43 to close the outlet 45, and pass forward through the tube 37 and retract the piston 27 to the position shown in Fig. 2. This causes the piston rod to pull the cable 20 and rotate the sheave 19 contra-clockwise, which also reels in the cable 14 causing the coupling 16 to pull against the pulley guide at 13 and retract the top of the door 1 and swing it on its pivots at 3. The door is stopped at a position slightly less than horizontal by the adjustable stop 50 on the wall 4, so that the door will automatically tend to close when the water pressure is stopped at the valve 35 by opening the remote control switch at 39.

When the switch at 39 is opened the valve automatically closes, and the spring 44 backs up the sleeve 43 and opens the outlet 45. In the meantime pressure leakage through the bypass 30-31, permits the starting spring 47 to advance the piston 27 past the outlet 45, permitting the water displaced by the advance of the piston to flow through the outlets 45 and 31 to the drain pipe 33.

By adjusting the needle valve 46 the advance of the piston can be selectively delayed to retard the closing of the door 1, from one to two or three minutes, sufficient time for the driver to dismount from the car and leave the garage through the door 1. In garages having other means of exit, the closing of the door 1 can be accelerated by adjusting the needle valves at 46 and 32.

The opening of the door can be made fully automatic by including the "electric eye" switch 51, in the circuit 40-41 preferably mounted within an opening through the door substantially aligned with the rays of the headlights of the motor car. It will function to close the circuit and open the door when activated by the headlights.

For doors of unusual height, the sheave 19 is easily changeable to increase or reduce the gear ratio between the sheaves 7-19. The board 6 and its mechanical assembly, may be mounted on either side of the door or the ceiling, whichever is the more practical.

Wherever electrical control is not available, a conventional stop valve may be substituted for the magnetic valve 35, and located at the post 42 or at any desired distance for remote manual control of the door opening mechanism.

The door may be maintained open by the latch 52 engaging a pin projecting from the wall 4.

Having fully described this invention and its mode of operation what I claim and desire to secure by Letters Patent is:

1. A fluid pressure unit comprising a cylinder having a stuffing box closing its forward end; a pressure supply tube discharging into the forward portion of said cylinder and connected with a source of fluid pressure and having a stop valve therein, a piston slidable within said cylinder and having a bypass therethrough open to said cylinder on opposite sides of said piston and a piston rod extending through said stuffing box; an intermediate valve interposed in said pressure supply tube and having a side outlet discharging into said cylinder behind said piston when the piston is in an advanced position and said stop valve is closed, so that the contents of the cylinder ahead of said piston may discharge through said supply tube, intermediate valve, and into said cylinder behind said piston when said piston moves forward.

2. A fluid pressure unit comprising a cylinder having a stuffing box closing one end; a pressure supply tube discharging into said cylinder adjacent said stuffing box and connected with a source of fluid pressure and having a stop valve therein; a piston slidable within said cylinder and having a piston rod extending through said stuffing box with a bypass open to said cylinder on the opposite sides of said piston; an intermediate valve interposed in said pressure supply tube and having a side outlet discharging into said cylinder behind said piston when the piston is in an advanced position and having a spring actuated sleeve opening said side outlet when said stop valve is closed; and a spring urging said piston forward when said stop valve is closed, so that the fluid pressure ahead of said piston may discharge through said supply tube, sleeve valve, and into said cylinder behind said piston.

3. A fluid pressure unit comprising a cylinder having a stuffing box closing its forward end and a head closing its other end and having a drain pipe therefrom; a pressure supply tube discharging into said cylinder adjacent said stuffing box and connected with a source of fluid pressure and having a stop valve therein; a piston slidable within said cylinder and having a piston rod extending through said stuffing box with a bypass in said rod open to said cylinder on the opposite sides of said piston; an intermediate valve interposed in said pressure supply tube and having a side outlet discharging into said cylinder head behind said piston when the piston is in an advanced position and having a spring actuated sleeve with a pressure passage therethrough and opening said side outlet when said stop valve is closed and closing said side outlet when said stop valve is open; and an expansive spring urging said piston forward when said stop valve is closed, so that the fluid pressure ahead of said piston may discharge through said supply tube, sleeve valve into said cylinder behind said piston and out through said drain pipe.

4. A fluid pressure unit comprising a cylinder having a stuffing box closing its forward end; a pressure supply tube discharging into the forward portion of said cylinder and connected with a source of fluid pressure and having a stop valve therein; a piston slidable within said cylinder and having a bypass therethrough open to said cylinder on opposite sides of said piston and a piston rod extending through said stuffing box; an intermediate valve interposed in said pressure supply tube and having a side outlet discharging

into said cylinder behind said piston when the piston is in an advanced position and said stop valve is closed, so that the contents of the cylinder ahead of said piston may discharge through said supply tube, intermediate valve, and into said cylinder behind said piston when said piston moves forward; and a control means remote from said cylinder for opening and closing said stop valve.

5. A fluid pressure unit comprising a cylinder having a stuffing box closing its forward end; a pressure supply tube discharging into the forward portion of said cylinder and connected with a source of fluid pressure and having a magnetically actuated stop valve therein; a piston slideable within said cylinder and having a bypass therethrough open to said cylinder on opposite sides of said piston and a piston rod extending through said stuffing box; an intermediate valve interposed in said pressure supply tube and having an outlet discharging into said cylinder in front of said piston when the piston

is in an advanced position and said stop valve is closed, so that the contents of the cylinder ahead of said piston may discharge through said supply tube, intermediate valve, and into said cylinder behind said piston when said piston moves forward; an electric circuit including said magnetic stop valve actuating means and having a remote control switch therein for opening and closing said circuit; and a movable object attached to said piston rod and normally exerting a pull thereagainst.
